UNITED STATES PATENT OFFICE

136,448

DESIGN FOR AN ILLUMINABLE CHRISTMAS ORNAMENT

William Kimmich, Medina, Ohio

Application June 24, 1943, Serial No. 110,520

Term of patent 3½ years

To all whom it may concern:

Be it known that I, William Kimmich, a citizen of the United States, residing at Medina, in the county of Medina and State of Ohio, have invented a new, original, and ornamental Design for an Illuminable Christmas Ornament, of which the following is a specification, reference being had to the accompanying drawing, forming part thereof.

In the drawing:

I claim:

The ornamental design for an illuminable Christmas ornament, as shown.

WILLIAM KIMMICH.
